CONVERSION OF HYDROCARBON OILS

Kenneth Swartwood, Chicago, Ill., assignor to
 Universal Oil Products Company, Chicago, Ill.,
 a corporation of Delaware

Application June 28, 1935, Serial No. 28,804

9 Claims. (Cl. 196—48)

This invention refers to an improved process for the selective conversion of relatively low boiling and high boiling hydrocarbon oils accompanied by reduction of the residual liquid conversion products of the process to coke in a high pressure coking zone of the system, wherein the vaporous products from the coking operation are subjected to continued conversion time in a high pressure reaction chamber together with other vaporous products of the process.

In one embodiment, the invention comprises subjecting low boiling components of the charging stock for the process, comprising a hydrocarbon oil of relatively wide boiling range, to vaporization by introducing the charging stock into a vaporizing chamber to which hot conversion products of the process are supplied, withdrawing the commingled vaporous low boiling components of the charging stock and vaporous conversion products from the vaporizing chamber and subjecting the same to additional conversion time in a high pressure reaction chamber, withdrawing liquid conversion products and non-vaporous high boiling components of the charging stock from the vaporizing chamber, subjecting the same to conversion conditions of cracking temperature and superatmospheric pressure in a heating coil and introducing the heated products into a coking chamber also maintained at substantial superatmospheric pressure, wherein their high boiling components are reduced to coke, withdrawing vaporous products from the coking chamber and introducing the same into said vaporizing chamber wherein they commingle with and effect said vaporization of the low boiling components of the charging stock, and wherein any high boiling components are separated therefrom and commingled with the high boiling, non-vaporous components of the charging stock, separating vaporous and liquid conversion products in the reaction chamber, returning the latter to the coking chamber without additional heating, subjecting the vaporous conversion products from the reaction chamber to fractionation, whereby their insufficiently converted components are condensed as reflux condensate and separated into selected relatively low boiling and high boiling fractions, returning the high boiling fractions of the reflux condensate to said heating coil for further conversion, subjecting the low boiling fractions of the reflux condensate to independently controlled conversion conditions of cracking temperature and superatmospheric pressure in a separate heating coil, introducing the heated products from said separate heating coil into the reaction chamber to commingle with and supply additional heat to the vaporous products supplied to this zone from the vaporizing chamber, subjecting fractionated vapors of the desired end boiling

point to condensation and recovering the resulting distillate.

As an alternative method of operation to that above outlined, which is not to be considered equivalent, the vaporous products from the coking chamber may be supplied, all or in part, directly to the reaction chamber wherein they are subjected to additional conversion, in which case the heated products from the last mentioned heating coil, to which said low boiling fractions of the reflux condensate are supplied, are introduced, all or in part, into the vaporizing chamber to effect said vaporization of the charging stock.

The features and advantages of the present invention will be more apparent with reference to the accompanying diagrammatic drawing and the following description thereof. The drawing illustrates one specific form of apparatus in which the process of the invention may be accomplished.

Referring to the drawing, heating coil 1 is located within a furnace 2 of any suitable form and the relatively high boiling oil supplied to this zone, in a manner to be later more fully described, is subjected therein to the desired conversion conditions of elevated temperature and superatmospheric pressure by means of heat supplied from the furnace. The hot conversion products are discharged from heating coil 1 through line 3 and valve 4 into coking chamber 5.

The coking chamber is also maintained at a substantial superatmospheric pressure and the high boiling components of the hot conversion products supplied to this zone are reduced therein to substantially dry coke. The coke may be allowed to accumulate within the chamber to be removed therefrom, in any well known manner not illustrated, when the chamber has been substantially filled or after its operation has been completed for any other reason. It is specifically within the scope of the invention to employ a plurality of coking chambers, although only one is illustrated in the drawing. When a plurality of such zones is employed the chambers preferably, are alternately operated, cleaned and prepared for further operation in order that the duration of the operating cycle will not be limited by the capacity of the coking zone. Chamber 5 is provided with a suitable drain line 6 controlled by valve 7, and this line may also serve as a means of introducing steam, water or any other suitable cooling material into the chamber after its operation has been completed in order to hasten cooling and facilitate the removal of coke therefrom.

Vaporous conversion products are withdrawn from the upper portion of coking chamber 5 through line 8 and may be directed, all or in part, through valve 9 in this line into vaporizing chamber 10 or they may be diverted, all or in part,

from line 8 through line 11 and valve 12 into reaction chamber 13.

Simultaneously with the operation above described charging stock for the process, preferably comprising hydrocarbon oil of relatively wide boiling range such as crude petroleum, topped crude or the like, is supplied through line 14 and valve 15 to pump 16, by means of which it is fed through line 17 and valve 18 and introduced into vaporizing chamber 10. The charging stock thus supplied to the vaporizing chamber is commingled in this zone with hot vaporous conversion products of the process from coking chamber 5 and/or from another source which will be later described, whereby the low boiling components of the charging stock are vaporized. The charging stock in turn serves to condense and remove from the vaporous conversion products supplied to chamber 10 any relatively high boiling components corresponding to the non-vaporous high-boiling components of the charging stock and the commingled relatively high-boiling liquids collect in the lower portion of the vaporizing chamber to be withdrawn therefrom through line 19 and valve 20 to pump 21, by means of which they are supplied through line 22 and valve 23 to conversion in heating coil 1, in the manner already described. The conversion products which remain uncondensed in chamber 10 and the vaporous low boiling components of the charging stock are withdrawn from the upper portion of this zone and directed through line 24 and valve 25 into reaction chamber 13, wherein they are subjected to additional conversion time under the conditions maintained in this zone.

Reaction chamber 13 is also operated at a substantial superatmospheric pressure and preferably the commingled materials supplied to this zone are directed by means of a suitable spreader flange or spray arrangement, such as indicated, for example, at 26, against the interior surface of the walls of the chamber in the upper portion thereof whereby their heavy liquid components come in contact with the chamber walls and are directed rapidly downward thereover, while their lower boiling vaporous components pass downward through the vapor space in the chamber and are subjected to appreciable continued conversion time during their passage therethrough. In the case here illustrated vaporous and liquid conversion products are separated within the lower portion of the reaction chamber, the liquid products being withdrawn from this zone through line 27 and valve 28 to pump 29, by means of which they are directed through line 30 and valve 31 to coking chamber 5 for further treatment and reduction to coke, while the vaporous products are withdrawn from a suitable point in the lower portion of the chamber, above the point of removal of the liquid products, and are directed through line 32 and valve 33 to fractionation in fractionator 34. It is, of course, also within the scope of the invention, although not here illustrated, to introduce the conversion products into the lower portion of chamber 13, in which case more rapid separation of their liquid components will be effected in this zone, to be directed therefrom, as previously described, to the coking chamber, while the vaporous products will be subjected to continued conversion as they pass upward through the reaction chamber, to be directed from the upper portion thereof to fractionation in fractionator 34.

The components of the vaporous conversion products supplied to fractionator 34 boiling above

the range of the desired final light distillate product of the process are condensed within this zone as reflux condensate and the reflux condensate is separated by fractional distillation into selected relatively low boiling and high boiling fractions which are separately subjected to further conversion within the same system, as will be later more fully described.

Fractionated vapors of the desired end boiling point are withdrawn, together with uncondensable gas produced by the process, from the upper portion of fractionator 34 and are directed through line 35 and valve 36 to condensation and cooling in condenser 37. The resulting distillate and gas passes through line 38 and valve 39 to collection and separation in receiver 40. Uncondensable gas may be released from the receiver through line 41 and valve 42. Distillate may be withdrawn from receiver 40 through line 43 and valve 44 to storage or to any other desired further treatment. When desired a regulated portion of the distillate collected in receiver 40 may be circulated, by well known means not illustrated in the drawing, to the upper portion of fractionator 34 to serve as a cooling and refluxing medium for assisting fractionation of the vapors and to maintain the desired vapor outlet temperature from the fractionator.

The high boiling fractions of the reflux condensate formed in fractionator 34 are withdrawn from the lower portion of this zone through line 45 and valve 46 to pump 47, by means of which they are fed through line 48 and may be directed, as desired, either through valve 49 in this line and line 22 to further conversion in heating coil 1, or, in case the boiling range and/or cracking characteristics of the high boiling reflux condensate are materially different than those of the liquid products supplied to heating coil 1 from chamber 10, as previously described, the high boiling reflux condensate may be directed from line 48 through line 50 and valve 51 to further conversion under independently controlled conditions in heating coil 52.

When heating coil 52 is utilized the oil supplied thereto is subjected to the desired conversion conditions of elevated temperature and superatmospheric pressure by means of heat supplied from a furnace 53 of any suitable form, and the hot conversion products are discharged from this zone through line 54 and valve 55 into coking chamber 5, wherein they commingle with the conversion products from heating coil 1 and wherein their high boiling components are reduced to coke.

The selected low boiling fractions of the reflux condensate formed in fractionator 34 may be removed from one or a plurality of suitable intermediate points in this one; provision being made in the case here illustrated for directing this material through line 56 and valve 57 to pump 58, by means of which it is supplied through line 59 and valve 60 to further conversion in heating coil 61. A furnace 62 of any suitable form supplies the required heat to the oil passing through heating coil 61 to subject the same to the desired conversion conditions of elevated temperature and superatmospheric pressure, and the heated products are discharged from the heating coil through line 63 and may be directed, all or in part as desired, either through valve 64 in this line and through lines 24 and 11 into reaction chamber 13, or through line 65 and valve 66 into vaporizing chamber 10. In case the total vaporous products from coking chamber 5 are directed

in the manner previously indicated to chamber 13, at least a regulated portion of the hot conversion products from heating coil 61 is introduced into chamber 10 in order to effect the desired vaporization of the charging stock in this zone. On the other hand, when the total or a substantial portion of the vaporous products from chamber 5 is supplied to chamber 10 the heated products from heating coil 61 may be introduced, as desired, into either chamber 10 or chamber 13, or in part to both. When all or a substantial portion of the heated products from heating coil 61 is introduced into chamber 10 the vaporous products from chamber 5 are preferably supplied direct to chamber 13, although they may when desired be introduced, all or in part, into chamber 10. By means of these alternative methods of operation the degree of vaporization to which the charging stock is subjected in chamber 10 may be controlled to suit requirements depending upon the characteristics of the charging stock and the other operating conditions of the process.

In the operation of the process of the present invention as it may be accomplished in an apparatus of the character illustrated and above described the preferred range of operating conditions may be approximately as follows: The first mentioned heating coil to which the high boiling fractions of the charging stock and liquid conversion products from the vaporizing chamber are supplied may utilize an outlet conversion temperature ranging for example from 800° to 950° F., preferably with a superatmospheric pressure at this point in the system of from 100 to 500 pounds or more per square inch. When a separate heating coil is employed for conversion of the high boiling reflux condensate conversion conditions within substantially the same range may be employed in this zone, although the specific conditions employed are preferably different from those employed in the first mentioned heating coil. The coking chamber is operated at a substantial superatmospheric pressure, which may be either substantially equalized or somewhat reduced relative to the pressure employed in the communicating heating coil utilizing the lowest pressure. The reaction chamber is preferably operated at substantially the same pressure as that employed in the coking chamber, although the pressure employed in the reaction chamber may be somewhat reduced when desired. The vaporizing chamber may be operated at substantially the same or at a higher pressure than that employed in the reaction chamber. The fractionating, condensing and collecting portions of the system may utilize substantially the same pressure as that employed in the reaction chamber or may be operated at substantially reduced pressures. The heating coil to which the selected low boiling fractions of the reflux condensate are supplied may utilize an outlet conversion temperature ranging for example from 900° to 1050° F., preferably with a superatmospheric pressure in this zone of from 200 to 800 pounds or more per square inch.

As a specific example of one of the many possible operations of the process of the present invention, the charging stock, which comprises a California crude of about 26° A. P. I. gravity, containing approximately 5% of material boiling up to 286° F., and approximately 18% at 400° F., is introduced into the vaporizing chamber, wherein its components boiling below approximately 660° F., which comprise about 50% of the charging stock, are vaporized. The non-vapor-

ous, high-boiling fractions of the charging stock are supplied, together with the liquid conversion products which accumulate in the vaporizing chamber, to a heating coil wherein the commingled relatively high boiling oils are subjected to a conversion temperature measured at the outlet from the heating coil of approximately 900° F., at a superatmospheric pressure of about 250 pounds per square inch. The high boiling fractions of the reflux condensate from the fractionator of the system are subjected in a separate heating coil to an outlet conversion temperature of approximately 925° F., at a superatmospheric pressure of about 250 pounds per square inch, and the heated products from both heating coils are introduced into the coking chamber, which is also maintained at substantially the same pressure. The vaporous products withdrawn from the coking chamber are introduced into the reaction chamber, which is also maintained at a superatmospheric pressure of about 250 pounds per square inch. Residual liquids are returned from the reaction chamber to the coking chamber, and the vaporous products from this zone are subjected to fractionation for the formation of light and heavy reflux condensates. The low boiling reflux condensate, approximately 90% of which boils within the range of 400° to 600° F., is subjected in a separate heating coil to an outlet conversion temperature of approximately 970° F., at a superatmospheric pressure of about 400 pounds per square inch. A sufficient portion of the highly heated products from this heating coil is introduced into the vaporizing chamber to effect the desired vaporization of the charging stock, and the remainder is introduced into the reaction chamber. This operation will produce per barrel of charging stock approximately 64% of motor fuel of good anti-knock value and approximately 65 pounds of coke, the remainder being chargeable to uncondensable gas.

I claim as my invention:

1. A process for the conversion of hydrocarbon oils which comprises, contacting charging stock for the process, comprising an oil of relatively wide boiling range, with hot vaporous conversion products of the process in a vaporizing chamber, withdrawing the resulting vaporous low boiling components of the charging stock and the commingled vaporous conversion products from the vaporizing chamber, introducing the same into a reaction chamber maintained under cracking conditions of temperature and pressure and wherein they are subjected to appreciable conversion, withdrawing non-vaporous high boiling components of the charging stock and commingled liquid conversion products from the vaporizing chamber, subjecting the same to conversion conditions of cracking temperature and superatmospheric pressure in a heating coil, introducing the heated products into a coking chamber wherein their high boiling components are reduced to coke, withdrawing vaporous products from the coking chamber, introducing the same into said reaction chamber to commingle with the vaporous products from the vaporizing chamber and be subjected to continued conversion therewith, separating vaporous and liquid conversion products in the reaction chamber, returning the latter to the coking chamber, subjecting vaporous products from the reaction chamber to fractionation for the formation of reflux condensate, subjecting fractionated vapors of the desired end boiling point to condensation, recovering the resulting distillate, subjecting reflux condensate

formed by said fractionation to independently controlled conversion conditions of cracking temperature and superatmospheric pressure in a separate heating coil, and introducing at least a regulated portion of the heated products from the said separate heating coil into the vaporizing chamber to commingle with and effect said vaporization of the charging stock.

2. A process for the conversion of hydrocarbon oils which comprises contacting charging stock for the process, comprising an oil of relatively wide boiling range, with hot vaporous conversion products of the process in a vaporizing chamber, withdrawing the resulting vaporous low boiling components of the charging stock and the commingled vaporous conversion products from the vaporizing chamber and introducing the same into a reaction chamber wherein they are subjected to appreciable conversion, withdrawing non-vaporous high boiling components of the charging stock and commingled liquid conversion products from the vaporizing chamber, subjecting the same to conversion conditions of cracking temperature and superatmospheric pressure in a heating coil, introducing the heated products into a coking chamber wherein their high boiling components are reduced to coke, withdrawing vaporous products from the coking chamber, introducing the same into said reaction chamber to commingle with the vaporous products from the vaporizing chamber and be subjected to continued conversion therewith, separating vaporous and liquid conversion products in the reaction chamber, returning the latter to the coking chamber, subjecting vaporous products from the reaction chamber to fractionation for the formation of reflux condensate, subjecting fractionated vapors of the desired end boiling point to condensation, recovering the resulting distillate, subjecting selected high boiling fractions of the reflux condensate formed by said fractionation to independently controlled conversion conditions of cracking temperature and superatmospheric pressure in another separate heating coil and introducing at least a portion of the heated products from the last mentioned heating coil into the vaporizing chamber to commingle with and effect said vaporization of the charging stock.

3. A process for the conversion of hydrocarbon oils which comprises, contacting charging stock for the process, comprising an oil of relatively wide boiling range, with hot vaporous conversion products of the process in a vaporizing chamber, withdrawing the resulting vaporous low boiling components of the charging stock and the commingled vaporous conversion products from the vaporizing chamber, introducing the same into a reaction chamber wherein they are subjected to appreciable conversion, withdrawing non-vaporous high boiling components of the charging stock and commingled liquid conversion products from the vaporizing chamber, subjecting the same to conversion conditions of cracking temperature and superatmospheric pressure in a heating coil, introducing the heated products into a coking chamber wherein their high boiling components are reduced to coke, withdrawing vaporous products from the coking chamber, introducing the same into said reaction chamber to commingle

with the vaporous products from the vaporizing chamber and be subjected to continued conversion therewith, separating vaporous and liquid conversion products in the reaction chamber, returning the latter to the coking chamber, subjecting vaporous products from the reaction chamber to fractionation for the formation of reflux condensate, subjecting fractionated vapors of the desired end boiling point to condensation, recovering the resulting distillate, subjecting selected high boiling fractions of the reflux condensate formed by said fractionation to independently controlled conversion conditions of cracking temperature and superatmospheric pressure in a separate heating coil, and introducing the resulting heated products into the coking chamber, subjecting selected low boiling fractions of the reflux condensate formed by said fractionation to independently controlled conversion conditions of cracking temperature and superatmospheric pressure in another separate heating coil and introducing at least a portion of the heated products from the last mentioned heating coil into the vaporizing chamber to commingle with and effect said vaporization of the charging stock.

4. A hydrocarbon oil conversion process which comprises fractionating cracked vapors, formed as hereinafter set forth, and separating relatively heavy and light reflux condensates therefrom, heating the light reflux condensate to cracking temperature under pressure in a heating coil and discharging resultant heated products into a vaporizing zone, introducing charging oil for the process to said vaporizing zone and therein separating vapors from unvaporized oil, heating the unvaporized oil and the heavy reflux condensate to conversion temperature under pressure independently of the light reflux condensate and distilling the same to coke in a coking zone, passing vapors from said coking zone and from said vaporizing zone into a reaction zone and therein subjecting the commingled vapors to continued conversion under cracking conditions, supplying vaporous conversion products from the reaction zone to the fractionating step as said cracked vapors, and finally condensing the fractionated vapors.

5. The process as defined in claim 4 further characterized in that said unvaporized oil and heavy reflux condensate are heated to conversion temperature while flowing in admixture through a second heating coil.

6. The process as defined in claim 4 further characterized in that said unvaporized oil and heavy reflux condensate are separately heated to conversion temperature prior to their introduction to the coking zone.

7. The process as defined in claim 4 further characterized in that additional vapors from the coking zone are introduced to the vaporizing zone to assist distillation of the charging oil therein.

8. The process as defined in claim 4 further characterized in that additional heated products from said coil are discharged directly into the reaction zone.

9. The process as defined in claim 4 further characterized in that additional heated products from said coil are discharged directly into the reaction zone and liquid conversion products from the reaction zone supplied to the coking zone.

KENNETH SWARTWOOD.
